(57) **CLAIM**

The ornamental design for a hydraulic press tool, as shown and described.

DESCRIPTION

FIG. 1 is a perspective view of a hydraulic press tool; FIG. 2 is a right side elevation view of the hydraulic press tool; FIG. 3 is a front elevation view of the hydraulic press tool; FIG. 4 is a left side elevation view of the hydraulic press tool; FIG. 5 is a rear elevation view of the hydraulic press tool; FIG. 6 is a top plan view of the hydraulic press tool; FIG. 7 is a bottom plan view of the hydraulic press tool; and, FIG. 8 is a cross-sectional view of the hydraulic press tool of FIG. 1 along line 8-8 of FIG. 6.

The elements shown in dash-dot broken line in the drawings are for the purpose of illustrating portions of the hydraulic press tool and form no part of the claimed design. The dot-dot broken line is for the purpose of illustrating the limit of the cross-sectional view taken along line 8-8 and forms no part of the claimed design.
